(57) **CLAIM**

The ornamental design for a ventilating fan, as shown and described.

DESCRIPTION

FIG. 1 is a perspective front view of a ventilating fan,

FIG. 2 is a top view thereof,

FIG. 3 is a bottom view thereof,

FIG. 4 is a rear view thereof,

FIG. 5 is a front view thereof,

FIG. 6 is a right side view, with respect to FIG. 2,

FIG. 7 is a left side view, with respect to FIG. 2; and,

FIG. 8 is a perspective bottom view thereof.

Any broken lines in the figures illustrate portions of the ventilating fan that form no part of the claimed design.
